DESIGN FOR AN AUTOMOBILE TRAILER BODY

Alexis de Sakhnoffsky, Philadelphia, Pa.

Application October 1, 1936, Serial No. 65,105

Term of patent 14 years

To all whom it may concern:

Be it known that I, Alexis de Sakhnoffsky, a subject of the Czarist régime, residing at Philadelphia, in the county of Philadelphia and State of Pennsylvania, have invented a new, original, and ornamental Design for an Automobile Trailer Body, of which the following is a specification, reference being had to the accompanying drawing, forming part thereof, wherein—

I claim:

The ornamental design for automobile trailer body substantially as shown.

ALEXIS DE SAKHNOFFSKY.
